(57) **CLAIM**

The ornamental design of a foldable cover for a motorcycle, as shown and described.

DESCRIPTION

FIG. 1 is a perspective view of the foldable motorcycle cover in use on a motorcycle.

FIG. 2 is a perspective view of the unfolded foldable motorcycle cover.

FIG. 3 is a top view of the foldable motorcycle cover.

FIG. 4 is a bottom view of the foldable motorcycle cover.

FIG. 5 is a left side view of the foldable motorcycle cover.

FIG. 6 is a right side view of the foldable motorcycle cover.

FIG. 7 is a front view of the foldable motorcycle cover.

FIG. 8 is a rear view of the foldable motorcycle cover; and, FIG. 9 is a perspective view of the folded foldable motorcycle cover.

In the drawings, the dotted broken lines in FIGS. 1 and 4 show stitching while the dashed broken lines in FIG. 1 depict a motorcycle that forms no part of the claimed design.
